AUTOMATIC STOKER

Weston M. Fulton, Knoxville, Tenn., assignor to
W. J. Savage Company, Inc., Knoxville, Tenn.,
a corporation of Tennessee

Original application October 9, 1939, Serial No.
298,661, now Patent No. 2,269,812, dated Janu-
ary 13, 1942. Divided and this application July
24, 1941, Serial No. 403,929

17 Claims. (Cl. 110—32)

This invention relates to automatic stokers for burning solid fuel, and more particularly to the "cross draft" type of stoker such as that generally described and shown in my U. S. Patent No. 2,126,104, granted August 9, 1938.

Cross draft stokers of the types now known and used possess a number of objectionable features. These defects and shortcomings are due in part to the stringent requirements of the domestic field in which these stokers are widely used. Domestic stokers are required to meet conditions quite different from power plant stokers. For example, domestic stokers are used principally in the heating of residences, small apartment houses, etc., where the heating load varies with the weather and consequently is subject to very wide extremes. Noise and dust must be avoided. Further, domestic stokers are cared for either by the house owner or by a domestic servant, the vast majority of whom are not familiar with mechanical devices and consequently neglect the mechanical upkeep of the stoker. Power plant stokers, on the other hand, operate under more uniform load conditions; are installed in industrial plants with other noisy machinery, need not be silent and are under the constant care of a skilled power plant engineer. Power plant stokers are usually installed at the time the power plant itself is installed, whereas the vast majority of domestic stokers are installed on heating plants of varying design that have been in service for a greater or less length of time with resulting installation difficulties not found in the power plant stoker.

Another objection to known stokers of the cross draft type is their inability to remain idle for protracted periods of time when the load demand drops to, or near, zero, and then promptly resume normal functioning when the demand abruptly and drastically increases. When these stokers are standing idle it is necessary to admit an appreciable amount of air to the combustion zone to create a "natural draft" through the chimney, or smoke pipe to which the stoker is connected. Otherwise smoke and fumes arising from the incandescent fuel in the burner would escape around the access doors of the stoker and fill the furnace room and work their way up into the living quarters of the house being heated. This "natural draft" produces slow combustion of the fuel in the stoker, and, if greatly prolonged, will consume all available fuel and the fire becomes very low. When demand is resumed and fresh fuel is fed into the stoker this fuel is consumed as fast as it is fed to the stoker and the fire has

great difficulty in building up again to normal proportions. This objection may be illustrated by reference to the shaker grate type of stoker in wide use in which fuel is discharged by gravity from the feed hopper to the shaker grate and moves slowly over the grate while being consumed. The rate of feed and rate of combustion are so timed that combustion will be completed as the moving fuel reaches the discharge end of the shaker grate. If the load demand drops and the stoker remains idle for a protracted period of time, the "natural draft" required to carry fumes away will consume all the fuel at the lower end of the shaker grate (this fuel having already been partially consumed), and consequently this portion of the grate will be covered with dead ash. When demand is resumed, all the cold air from the blast fan which passes through the lower portion of the grate will find no fuel with which it may combine and will mingle with the hot gases rising from the burning fuel at the upper end of the grate, cooling these gases and reducing their heating effect. Furthermore, since the rate of feed and rate of combustion are timed for normal working conditions under a fairly constant load, the feeding device is now lacking in capacity to supply sufficient fuel for actual combustion plus a surplus sufficient to again cover the lower portion of the shaker grate. Various devices such as the so-called "automatic air controls" for adjusting the air supply to correspond with the thickness of the fuel bed have been produced in an effort to cure this defect in these stokers, but these devices have met with little more than indifferent success.

Another objection to known stokers of the cross draft type, to which the present invention pertains, is that they have hitherto failed to provide ready access of air to that portion of the fuel lying against the opposing wall sections of the combustion chambers. In stokers utilizing the cross draft principle the distance between the front and rear sections of the combustion chambers must be relatively small to maintain a relatively thin fire-bed, since in a thick fire-bed the temperature of combustion reaches such a high point that large, unwieldy clinkers are formed in the combustion chambers, clogging the latter and making ash disposal difficult. Hollow, water-cooled members in close proximity to each other and in physical contact with the burning fuel have been used to rapidly conduct heat away from the fuel and prevent the temperature of the latter from rising materially above the fusing point of the ash. This expedient fails when the

fire-bed is very thick since a region will still exist midway between the front and rear sections where high temperatures will prevail and objectionable clinkers will form. When a thin fire-bed is used the width of the front and rear sections of the combustion zone has been relatively large. Hence there are zones, or pockets in the fuel bed where the latter lies against these front and rear sections which the air cannot reach since the tendency of the air is to pursue a straight-line course through the fuel and the slight resistance to the progress of the air offered by the fuel in a relatively thin fire-bed is not sufficient to cause the air to diffuse in the burning zone. This results in uneven burning of the fuel, fusion and consequent sticking of the fuel in the pockets referred to and arching of the entire fuel bed in the combustion chambers.

Still another defect in known stokers of the cross draft type is that hitherto only gravity discharge of the ash has been possible. The presence of foreign matter in the fuel has resulted in clogging the ash discharge in the absence of positive mechanical means for forcing obstructions out of the path of ash flow.

Another defect in known cross draft stokers is the tendency of radiant heat to escape from the incandescent fuel through the openings of the inlet tuyères causing a substantial waste of heat. Some smoke and fumes occasionally escape through the inlet tuyères as well.

Another defect in known cross draft stokers is that fine particles of incombustible matter given off from the burning fuel lodge in the passageways of the heater. This incombustible matter, known as "fly-ash," is greatly increased in quantity by the forced draft usually provided with these stokers. No satisfactory method has hitherto been devised for automatically disposing of this "fly-ash."

A still further defect of the known cross draft types of stokers is that a suitable amount of fire travel between the burning fuel and the heating surface of the boiler cannot be provided. To those skilled in the art it is well known that the flame generated by burning fuel is composed of a mixture of hot gases which are rapidly undergoing chemical changes and these changes proceed to completion only after the flame has travelled a considerable distance away from the burning fuel. If these hot gases come into contact with any relatively cool surface, such as the crown sheet of a boiler, and are thereby cooled below the temperature of ignition of the component gases before combustion has been completed, chemical change will be arrested and the temperature of combustion will fall short of its maximum reducing the heating effect and wasting fuel. This is a matter of such importance that heating inspectors in many localities require that all stokers installed within their jurisdiction have a specified minimum distance between the stoker or burner and the heating surface of the boiler.

It is accordingly an object of the present invention to provide a novel cross draft type of stoker which is suitable for general requirements, particularly domestic, and which is readily adaptable for use with existing heating plants.

Another object of the present invention is to provide a novel cross draft type of stoker which can after long periods of idleness promptly resume normal operation when the heat demand is increased.

Another object of the present invention is to

provide a novel cross draft type of stoker in which combustion supporting gases may reach every portion of the burning zone.

Another object of the present invention is to provide a novel cross draft type of stoker in which the formation of clinkers is reduced to a minimum.

Another and still further object of the present invention is to provide a novel cross draft type of stoker in which more fuel is supplied to the burning zones than is required for the normal operation of the stoker.

Another and still further object of the present invention is to provide a novel cross draft type of stoker in which novel means are provided for distributing the fuel to the burning zones and returning surplus fuel to the source of fuel supply.

Another and still further object of the present invention is to provide a novel cross draft of stoker which is silent in operation, efficient, compact, relatively inexpensive to manufacture and install, and which may be operated without prior knowledge or training.

Other and further objects of the present invention will appear as the description thereof proceeds.

With these objects in view, an illustrative embodiment of the cross draft stoker of the present invention is shown in the accompanying drawings but it is to be expressly understood that this embodiment of the present invention is shown in the accompanying drawings and hereafter described for the purposes of illustration only and is not to be construed as a limitation on the present invention. Reference should be had to the appended claims to determine the scope of the present invention.

In the accompanying drawings,

Fig. 1 is a front elevation of one embodiment of the novel cross draft stoker of the present invention shown installed with a boiler of the usual type and having a portion of the front of the stoker jacket broken away to show the front of the stoker;

Fig. 2 is a side elevation as seen from the left of the embodiment of the present invention shown in Fig. 1;

Fig. 3 is a view of the embodiment of the present invention shown in Fig. 1 as seen from above with the top of the jacket and the top of the fuel scraper cut away;

Fig. 4 is a cross-sectional elevation on the line 4—4 of the embodiment of the present invention shown in Fig. 1;

Fig. 5 is a cross-sectional elevation of the embodiment of the present invention shown in Fig. 1 taken at right angles to the section of Fig. 4;

Fig. 6 is a sectional view on the line 6—6 of the embodiment of the present invention shown in Fig. 1, the electric motor and fan being omitted for clarity;

Fig. 7 is a sectional elevation of a novel fuel conveying mechanism suitable for use in conjunction with the embodiment of the present invention shown in Fig. 1; and

Fig. 8 is an enlarged view of the clutch mechanism shown in Fig. 7.

Referring now to the accompanying drawings in which like reference characters indicate similar parts and more particularly to Fig. 1, the stoker 25, made up of hollow sections is connected to the boiler 26 by means of pipes 27 and 28, in accordance with the practice known to the art for stokers of this type to permit free exchange

of water and steam between the boiler and stoker. Combustion of fuel takes place in the stoker 25 and the hot products of combustion pass through the stoker outlet 29 into the ash pit 30 of boiler 26 thence upward through the heating passageways of boiler 26 and out through the smoke-hood to the smoke-pipe. It has hitherto been the practice to apply forced draft to stokers of this type. In the present invention, an induced draft is used. To create the desired induced draft an electric motor 33, supported on bracket 34 attached to stoker 25, carries the rotor of a blower 36 (Fig. 3) on the end of the motor shaft. Said blower discharges air through pipe 38 into the air intake 39 of ejector 40 which is in communication through chamber 51 with suction chamber 42. Pipe 41 extends from smoke-hood 31 to said suction chamber 42 of ejector 40 and the gases are delivered through pipe 32 to any suitable chimney or stack (not shown). Motor shaft 37 has pulley 43 keyed thereon and belt 44 transmits power from pulley 43 to pulley 45 which is keyed to shaft 46 of speed reducer 47 of any standard construction.

Referring more particularly now to Figs. 1 and 2, fuel hopper 60 is provided with lid 61 hinged at 62 and provided with a handle 63. A metal jacket, or covering, 64 surrounds stoker 25 and extends to the bottom 65 thereof to form a substantially air-tight closure around stoker 25. At the top of jacket 64, and in communication with the interior thereof, is vent pipe 66. Pipe 66 leads to any suitable outlet such as the chimney used with boiler 26; it may connect to ash pit 30 of boiler 26; or, as here shown, it may connect at 67 to smoke pipe 32. Jacket 64 has adjacent its top, and immediately above combustion chambers 68 (Fig. 4), two openings 69, which are provided with lids 70 hinged at 71 and provided with handles 72. Each handle 72 has a round extension 73 journaled in lug 74 integral with lid 70. Extension 73 carries latch 75, which, when lid 70 is closed, can be rotated to engage reinforcing member 80. Each lid 70 is opened by rotating handle 72 to disengage latch 75 and lid 70 can then be raised to the open position shown in dotted outline at the left in Fig. 4. This arrangement permits access to combustion chambers 68 for starting the fire in the stoker and gives access to the working parts.

Referring now to Figs. 1 to 6, inclusive, it will be seen that the combustion chambers 68 of my improved stoker are built up of a plurality of hollow sections spaced from each other and secured together by a plurality of hollow nipples which are screwed into suitable threaded bosses or openings in each section. As shown in Fig. 6, hollow side sections 111 and 112 have mounted therebetween one or more hollow outside sections 113 and an equal number of inside hollow sections 114. Combustion takes place in the combustion chambers 68, inclosed by side sections 111 and 112, outside sections 113 and inside sections 114, and the hot gases from the burning fuel pass out through the central chamber 116 formed by inside sections 114. Outside sections 113 are identical in construction, being hollow to provide passages through which water may freely circulate and having their lower portions downwardly and inwardly inclined towards the middle of the burner so that said lower portions are closer at their lower extremities, as is apparent from Fig. 4, than at their upper extremities. The inside sections 114 are also hollow to provide passages through which water can freely circulate, and

have ribs 119 formed integrally therewith, the spaces 120 between ribs 119 constituting tuyères through which the hot gases of combustion enter central chamber 116. Side sections 111 and 112 have ribs 125 formed integrally therewith with spaces 126 therebetween so that when assembled said sections form companion tuyères with those formed by the inside sections 114.

Side section 111 has therein a cylindrical opening 127 surrounded by extension 128 into which is fitted a cylindrical member 129 suitably secured thereto, by any convenient means here shown as by screws 130, and extending into chamber 116. Member 129 forms an outlet 131 through which the gaseous products of combustion pass in their travel to boiler 26. Member 129 may be made of any suitable heat-resisting material such as fire-clay or any of the heat-resisting alloys. Member 129 is so designed that the hot gases of combustion emerging from tuyères 126 nearest opening 127 must travel to the opposite side of stoker 25 before escaping through open end 131 of member 129 to give the gaseous products of combustion a long path of travel and ample time in which the chemical reactions of combustion may be completed before the gaseous products of combustion come into contact with the relatively cool interior passageways of boiler 26. As member 129 is exposed to the hot gases of combustion emerging from tuyères 126 its outer and inner surfaces are maintained at high temperatures. The gases in contact with and surrounded by these surfaces will therefore be held at a temperature above the temperature of ignition of the component elements of the gases until they emerge from opening 127. Adequate fire travel to insure complete combustion is thus provided by the present invention.

Inside sections 114 are V-shaped in cross section (Fig. 6) with the apex of the V pointing towards combustion chambers 68. Outside sections 113 are also V-shaped with the apex of the V pointed towards combustion chambers 68. Sections 113 have no tuyère forming ribs. Hollow hubs 132 (Fig. 3) formed on sections 113 project a sufficient distance beyond the sides of sections 113 to form suitable spaces therebetween in which oscillating tuyère members 133 having upwardly and then downwardly inclined air passages 146, 147 (see Figs. 4 and 6) are mounted for reciprocation. As said oscillating tuyère members 133 and the means for operating the same have been fully disclosed in my application Serial No. 298,661 filed October 9, 1939, issued as Patent No. 2,269,812, January 13, 1942 to which cross reference is made, a detailed explanation herein is unnecessary.

Referring more particularly to Fig. 4, formed adjacent the lower ends of side sections 111 and 112 are plates 171. Plates 171 are provided with offsets 172 having extensions 173. Also formed on sections 111 and 112 are lugs 174 designed to receive plates 175 positioned between sections 111 and 112, plates 175 having their upper ends supported by lugs 174 and their lower ends supported in offsets 172. Plates 175 catch any dust or ash which may sift through tuyères 133 and direct this waste matter downward into the ash discharge. Suitably secured to plates 171 are curved plates 176 which close the space between sections 111 and 112 and extend forwardly to a point adjacent the front of the stoker. Plates 176 deflect the ash traveling downward from combustion chambers 68 into opening 177 of a suitable ashpit 178. Plates 176 are here shown

secured to the left sides (Fig. 4) of sections 111 and 112 but it is to be understood that plates 176 can be connected at the right if desired. Ashpit 178 would then be located near the left side of Fig. 4, this feature rendering installation of the stoker more flexible.

As is best seen in Figs. 4 and 5, a suitable member 179 is spaced from and covers the top of stoker sections 114 providing a suitable space 180 around it in which scrapers 181 may move with ample clearance. Member 179 prevents fuel from accumulating in the space on top of stoker sections 114.

Stoker side section 111 is provided with a hollow, water-cooled outlet 29 (Figs. 5 and 6) for conducting the hot gaseous products of combustion from outlet 121 and member 129 into boiler 26. Outlet 29 is of suitable cross section here shown as rectangular and is downwardly directed to deliver the hot gases of combustion at, or near, the bottom of boiler 26, as may be seen in Fig. 1. Outlet 29 has vertically disposed ribs 184 and 185 suitably secured to opposite walls 182 and 183 to which are attached cross members 186 and 187 forming dust-collecting passages 188 and 189 therebetween. Cross members 186 and 187 have their upper edges turned outwardly towards the center of outlet 29 and are suitably separated from each other to form traps by which fly-ash and dust particles may enter passages 188 and 189. Passages 188 empty into a suitable passage 190 which in turn empties into dust-collecting chamber 191. Passages 189 are divided into two branches 193 (Fig. 5) which straddle outlet 29 and discharge into dust chamber 191. A suitable passage 194 connects dust chamber 191 and outlet 29. The area of passage 194 is greater than the area of passage 190. When induced suction or draft is applied to outlet 29 through boiler 26 to which it is connected, gases can escape from dust chamber 191 through passage 194 faster than they can enter through passage 190 producing a reduced pressure inside chamber 191. Mounted in chamber 191 is conveyor screw 195 journaled at 196 in wall 197 of chamber 191 and having its discharge end 198 loosely mounted in a suitable cylindrical hub 199 opening into ash discharge passage 200. End 198 of screw 195 terminates short of the entrance of hub 199 into ash discharge passage 200 to permit a suitable quantity of dust or fly-ash to accumulate in hub 199 to form a seal or plug to prevent air from being drawn into chamber 191 through ash discharge 200.

Referring to Figs. 3, 4 and 5, a second reduced speed shaft 213 of speed reducer 41 passes through jacket 64 and is journaled in bracket 737 fixed to top member 238 of fuel hopper 60. Suitable packing means may be used to insure a gastight joint where shaft 213 passes through jacket 64. Secured to shaft 213 is bevel pinion 240 which meshes with pinion 241 fixed to drive shaft 242 of conveyor screw 243. Spur gear 244 likewise fixed to conveyor shaft 242 meshes with idler gear 245 which in turn meshes with spur gears 246 and 247. Gear 246 is fixed to drive shaft 248 of secondary conveyor screw 249. The general construction and operation of conveyor screws 243 and 249 here shown and generally described is the same as that shown and described in detail in my copending application Serial No. 253,930, filed January 31, 1939, for "Improvements in feeders." A spider frame 260 has four arms 261 secured to the lugs 262 formed on side sections 111 and 112. Fixed to spider

frame 260 are studs 263 to which are journaled sprockets 264 and 265. Spur gear 247 is fixed to shaft 266 which rotates in its stud 263 and carries sprocket 264 fixed thereto. The other sprocket 265 turns idly on their studs 263. Sprocket 264 drives sprocket chain 267 and sprockets 265 support and stretch chain 267. Chain 267 carries a plurality of scrapers 181 pendant therefrom.

As is well known to those skilled in the art to which this invention pertains, stokers of this type are controlled by an electric switch in turn controlled by any convenient means such as a thermostat located in the building being heated.

Assuming that the above described embodiment of the present invention is set up as above described, to place it in operation lids 70 of jacket 64 (Fig. 5) are opened and pieces of ignited material (paper, excelsior, wood shavings, etc.) are dropped into combustion chambers 68 followed by wood kindling, after which coal (or other solid fuel) is supplied with a shovel until chambers 68 have been filled up to the level of the lower edges of scrapers 181. Lids 70 are then closed and secured by turning handles 72 to rotate latches 75 into engagement with members 80. Electric motor 33 is then started putting blower 36 into operation and closing damper 92 in vent pipe 66 and openings dampers 106 in the lower sides of jacket 64. The air supplied through air duct 38 from blower 36 to ejector 46 produces an induced draft or suction in smoke-hood 31, in boiler 26 and in stoker 25 causing air to be drawn in through damper openings 106, through tuyeres 133 through the burning fuel in chambers 68, and causing the hot gases of combustion to be drawn through tuyeres 120, 126, through cylindrical member 129 and through outlet member 29 into boiler 26 as indicated by arrows in Figs. 4, 5 and 6. This vigorous in draft of air through the stoker causes the fuel in combustion chambers 68 to ignite rapidly until combustion is taking place throughout combustion chambers 68 up to the zones indicated by dotted lines 210 (Fig. 4). As there are no inlet and outlet tuyeres above the zones indicated by lines 210 the fuel in this space receives insufficient air to support combustion. Particles of dust, or "fly-ash," that may be held in suspension in the hot gaseous products of combustion are thrown out of the gaseous stream in turning the reverse curve in outlet member 29 at high velocity by the action of centrifugal force and are caught by the outwardly protruding edges of cross members 186 and 187 and deflected through the passages between these cross members into the passages 188 and 189. The reduced pressure in dust chamber 191 causes the particles thus trapped to be drawn or sucked through passages 190 and 193 into dust chamber 191. At the same time that electric motor 33 starts blower 36 it drives pulley 45 of speed reducer 41 through belt 44 driven by pulley 43 secured to motor shaft 37.

Thereby the tuyeres 133 are oscillated from cranks 232 and 233 as more particularly explained in my application Serial No. 298,661. Reciprocation of tuyeres 133 produces many desirable results heretofore not obtained. It agitates the fuel in combustion chambers 68 breaking up arching, prevents formation of holes in the fuel bed due to "burning through" and works the fuel downward in combustion chambers 68. Reciprocation of tuyeres 133 also produces a better distribution of air entering the fuel bed by constantly moving the tuyere openings to different

positions relative to the fuel. As the fuel is worked downward in chambers 68 and combustion proceeds the fuel is reduced to ashes and its volume is reduced.

Because stoker sections 113 are V-shaped in cross section the incoming air in passing through tuyeres 133 which are likewise V-shaped in cross section is allowed to spread laterally before it reaches the fuel in combustion chambers 68. The V-shaped cross section of center stoker sections 114 allows the gaseous products of combustion to converge after passing through the fuel in combustion chambers 68 before entering chamber 116. Air is therefore conducted to every portion of the burning fuel in chambers 68 preventing the formation of pockets of unburnt fuel and increasing the efficiency of the stoker.

Simultaneously with the operations just described, reduced speed shaft 213 (Fig. 5) rotates bevel pinions 240 and 241 and rotates conveyor screws 243 and 249 which in turn elevate fuel from hopper 60 and discharge it into the space 180 at the top of the stoker. This fuel is then picked up by scrapers 181 and distributed uniformly around the space 180, scrapers 181 being driven by sprocket chain 267, sprocket wheel 264, and gear wheels 244, 245 and 247. The speed of shaft 213 is so adjusted with respect to the gear ratios that conveyor screws 243 and 249 will supply fuel to stoker 25 faster than stoker 25 can consume it. The surplus fuel not consumed is carried around space 180 by scrapers 181 and discharged over wall 336 (Fig. 3) back into the hopper 60. When the stoker of the present invention remains idle for prolonged periods of time the fuel in space 180, above the dotted lines 270, serves as a reserve to replenish the fuel consumed by the slow combustion in combustion chamber 68 resulting from natural draft, and as this reserve is slowly consumed the fuel level in space 180 drops down towards dotted lines 270. When demand for heat is resumed and the stoker is again put into operation conveyor screws 243 and 249 supply fuel faster than it can be consumed and space 180 is quickly refilled and the fuel level is brought back up to the bottom edges of scrapers 181, after which the surplus fuel is again discharged back into hopper 60, as described. It is to be understood that while in the preferred embodiment of the present invention the surplus fuel is returned to the hopper it may be disposed of in any other way desired as for example by discharging it into a separate bin, or hopper, provided for that purpose.

In some installations and particularly for domestic uses it may be desirable to equip stokers of the present invention with a "bin feed" rather than providing a fuel hopper 60. In such an installation fuel is fed to the stoker directly from any suitable bin which may contain the full season's supply of fuel and which is usually constructed as an integral part of the structure of modern homes. While any suitable type of "binfeed" may be used in conjunction with the stoker of the present invention a preferred bin feed is shown and illustrated in Figs. 7 and 8. As is there shown, stoker 25 is suitably mounted on the floor 271 of the conventional boiler room having a well 272 of relatively small capacity sunk below floor 271 and lined with any suitable material such as concrete, sheet iron or the like. Fuel is fed into well 272 from a suitable large capacity bin 274 by any suitable means here shown as conveyor screw 275 installed in a suitable trough 276 located beneath floor 271. Bin

274 may be of suitable design here shown as having a vertical wall 277, an inclined wall 278 and provided with a suitable opening 279 through which fuel flows by gravity to the intake end of screw 275. Trough 276 is closed at the intake end by member 280 having a hub 285 in which conveyor screw 275 is journalled. Well 272 is provided at its lowest point with a recess 286 carrying therein a bearing plate 287 in which conveyor screws 243 and 249 are journalled. Conveyor screws 243 and 249 are enclosed within a sheet metal casing 288 reinforced at its base by angle iron 289 suitably secured thereto as by rivets 290 which likewise secure bracket 291 to casing 288. Bracket 291 extends outwardly and downwardly and terminates in a suitable hub 292 which provides a bearing for screw 275. A sprocket 293 is secured to screw 275 and is driven by sprocket chain 294. Shaft 213 is extended beyond bracket 237 and has mounted thereon the cone section 295 of a suitable cone clutch. A key fixed to shaft 213 fits loosely in a suitable keyway in cone section 295 to rotate cone section 295 with shaft 213 but permits free lengthwise travel of cone section 295 on shaft 213. Shaft 213 is of reduced diameter at 297. Mounted loosely on section 297 is sprocket 298. Secured to sprocket 298 is the concave section 299 of the cone clutch, and secured to the opposite side of sprocket wheel 298 is hub 300. Secured to hub 300 is end 301 of coil spring 302. End 303 of spring 302 engages pin 304 projecting from grooved pulley 305. Hub 300 is of reduced diameter at 306 and is threaded at 307 to carry pulley 305 which is threaded loosely thereon. Bracket 237 is provided with a suitable hollow cylindrical hub 308 to slidably receive hollow hub 309 of transverse member 310. Hub 309 slidably supports rod 311 to which is secured segment 312. Segment 312 engages the groove of grooved pulley 305. Secured to the upper portion of segment 312 is U-shaped member 313 made of tempered spring steel or other suitable resilient material and having arms 314. Arms 314 of member 313 are bifurcated to receive pins 315 on which are pivotally mounted toggles 316. Toggles 316 are pivoted together on pin 317. Link 318 is likewise pivoted on pin 317 and its opposite end is pivoted at 319 to member 310. Arms 314 of member 313 exert a strong pressure against toggles 316 tending to press toggles 316 inward towards pin 317. Transverse member 310 engages a suitable groove 320 formed in the cone section 295. Rod 321 pivotally engages a stud 322 projecting from pulley 305 and extends downwardly inside casing 288 and passes through and is guided by a bracket 323 suitably secured to casing 288. Below bracket 323 rod 321 divides into two branches 324 which straddle bracket 291 and carry a shoe 325. A suitable opening 326 is provided in top member 238 to permit rod 321 free movement in all directions. Sprocket chain 294 passes through opening 327 in member 238 and engages sprocket wheel 298. When clutch member 295 is in engagement with companion clutch member 299, the latter, together with sprocket 298, hub 300 and pulley 305 will be rotated by shaft 213, pulley 305 being driven by the engagement of spring 302 and pin 304. Rotation of sprocket 298 drives sprocket chain 294 and rotates sprocket 293 rotating conveyor screw 275 and feeding fuel from fuel bin 274 into well 272. At the same time rod 321 is being reciprocated by the rotation of pulley 305. The speed of conveyor screw 275 is adjusted to

feed fuel from bin 274 to well 272 faster than conveyor screws 243 and 249 can supply it to stoker 25. Consequently well 272 will become filled with fuel and the top of the fuel rises until it contacts shoe 325. Contact of shoe 325 with the fuel prevents further reciprocatory movement of rod 321 and prevents pulley 305 from rotating. Shaft 213 will continue to rotate hub 300 rotating screw threads 307 in pulley 305 forcing pulley 305 to the left (as seen in Fig. 7). Movement of pulley 305 to the left will carry segment 312 to the left and draw spring member 313 to the left, link 318 meanwhile holding pin 317 stationary until pins 315 pass slightly to the left of pin 317 whereupon the end thrust exerted by spring 313 against toggles 316 will snap pin 317 to the right forcing member 310 and cone section 295 to the right disengaging the clutch. Pulley 305, hub 300, sprocket 298 and clutch member 299 are now stationary while shaft 213 continues to rotate and drive conveyor 243. The resilience of spring 302 and the load on sprocket 298 are so proportioned that the reaction of spring 302 against pin 304 of pulley 305 will not be sufficient to drive sprocket 298 in the reverse direction when cone section 295 is disengaged. As conveyor 243 gradually exhausts the supply of fuel in well 272, the top of the fuel pile will drop from beneath shoe 325 until rod 321 is free to reciprocate. Spring 302 will now rotate pulley 305 in a counterclockwise direction as seen in Fig. 8 and screw threads 307 will carry pulley 305 to the right to reverse the cycle of operations above described, engage the clutch elements 295 and 299 and drive conveyor 275.

It will now be apparent that the present invention provides a novel cross draft type of stoker which is particularly suited for domestic installation; which is silent, efficient, compact, relatively inexpensive and flexible in installation; which can, after periods of idleness, promptly resume normal operation; in which combustion supporting gases reach every portion of the burning zone to reduce the formation of ashes and clinkering; in which positive means are provided to assist the gravity discharge of ash; and in which automatic means are provided for removing entrained particles in the gases of combustion. The present invention further provides a novel cross draft type of stoker in which a suitable amount of fire travel is provided to insure complete combustion of the gases of combustion; in which more fuel is fed to the burning zones than is required for the normal operation of the stoker; and in which novel means are provided for distributing the fuel to the burning zones.

This application is a division of my application Serial No. 298,661, filed October 9, 1939, issued as Patent No. 2,269,812, January 13, 1942, for Automatic stokers. Provisions herein disclosed concerned with the flow of fumes and air from and through the stoker, both when the stoker is idle and when it is in operation, are claimed in a separate division of my aforesaid application.

What is claimed is:

1. In a cross draft stoker, in combination with walls providing a combustion chamber, means for maintaining a body of fuel in said chamber during combustion and a source of solid fuel, fuel feeding means for feeding said fuel to the top of said chamber, said fuel feeding means being constructed to supply fuel to said chamber at a rate in excess of the rate at which the fuel is normally consumed in said chamber, said combustion chamber having a fuel discharge opening

at the normal level of fuel in said chamber, fuel distributing means for spreading the fuel delivered to said chamber on top of the body of fuel in said chamber, said distributing means being horizontally aligned with said opening and movable into adjacency thereto to remove surplus fuel from the top of said chamber when said chamber is full, and motive means for driving said fuel feeding and said fuel distributing means.

2. In a cross draft stoker, in combination with walls providing a combustion chamber, means for maintaining a body of fuel in said chamber during combustion and a source of solid fuel disposed below the top of said chamber, fuel feeding means for elevating said fuel to the top of said chamber, said fuel feeding means being constructed to elevate fuel to said chamber at a rate in excess of the rate at which the fuel is normally consumed in said chamber, fuel distributing means for spreading the fuel delivered to said chamber on top of the body of fuel in said chamber, said chamber having a fuel discharge opening at the normal level of fuel in said chamber, means extending downwardly from said opening to said source of fuel for returning fuel to said source of fuel, said distributing means moving into adjacency to said opening to move surplus fuel from the top of said chamber through said opening when said chamber is full, and motive means for driving said fuel feeding and said fuel distributing means.

3. In a cross draft stoker, in combination with inner and outer walls provided with tuyères to form a combustion chamber, said walls extending upwardly above said tuyères to provide a fuel receiving chamber above the zone of burning fuel in said combustion chamber, fuel feeding means for delivering fuel to the top of the fuel in said receiving chamber, means in said fuel receiving chamber for spreading the fuel delivered by said fuel feeding means with substantial uniformity over the top of the fuel in said receiving chamber, and motive means for driving both of said fuel feeding means and said fuel spreading means.

4. In a cross draft stoker, in combination with a source of fuel, spaced exterior and interior walls defining a combustion chamber, said exterior and interior walls having openings for the ingress of combustion air and egress of products of combustion, said ingress and egress openings defining a fuel burning zone in said combustion chamber and said inner and outer walls extending above said openings to define a fuel receiving zone above said fuel burning zone, fuel feeding means for elevating fuel to the top of the fuel in said fuel receiving zone, fuel spreading means disposed above the fuel in said fuel receiving zone and movable over the fuel in said fuel receiving zone for evenly distributing the delivered fuel on the top of the fuel in said receiving zone, and motive means for driving both said fuel feeding means and said fuel spreading means.

5. In a cross draft stoker, in combination with spaced exterior and interior walls defining a combustion chamber, said exterior and interior walls having openings for the ingress of combustion air and egress of products of combustion, said ingress and egress openings defining a fuel burning zone in said combustion chamber and said inner and outer walls extending above said openings to define a fuel receiving zone above said fuel burning zone, fuel feeding means for delivering fuel to the top of the fuel in said fuel receiving zone, fuel spreading means acting on

the fuel delivered to the top of the fuel in said fuel receiving zone for evenly distributing the delivered fuel on the top of the fuel in said receiving zone, said fuel spreading means including scraping means and driving means for said scraping means for moving said scraping means through a closed horizontally disposed path, and motive means for driving both said fuel feeding means and said fuel spreading means.

6. In a cross draft stoker, in combination with spaced exterior and interior walls defining a combustion chamber, said exterior and interior walls having openings for the ingress of combustion air and egress of products of combustion, said ingress and egress openings defining a fuel burning zone in said combustion chamber and said inner and outer walls extending above said openings to define a fuel receiving zone above said fuel burning zone, fuel feeding means for delivering fuel to the top of the fuel in said fuel receiving zone, fuel spreading means acting on the fuel delivered to the top of the fuel in said fuel receiving zone for evenly distributing the delivered fuel on the top of the fuel in said receiving zone, said fuel distributing means including a plurality of scrapers, an endless flexible drive element carrying said scrapers and disposed horizontally, means for driving said drive element through a closed path whereby said scrapers are circulated to level the top of the fuel in said fuel receiving zone, and motive means for driving both said fuel feeding means and said fuel spreading means.

7. In a cross draft stoker, in combination with exterior and interior walls provided with ingress openings for combustion supporting air and egress openings for products of combustion, said openings defining a combustion supporting zone and said walls extending above said combustion supporting zone to define a fuel receiving zone from which fuel descends by gravity to replenish the fuel in said combustion supporting zone, means for feeding fuel to the top of said fuel receiving zone, said fuel feeding means being constructed to supply fuel to said fuel receiving zone at a rate in excess of the rate at which the fuel is normally consumed in the combustion supporting zone, means movable substantially horizontally through a closed path and acting on the fuel delivered by said fuel feeding means for distributing the received fuel evenly on top of the fuel in said fuel receiving zone, a fuel discharge opening communicating with said fuel receiving zone at the normal fuel level therein, said fuel distributing means moving into adjacency to said opening to displace therethrough the excess fuel when said fuel receiving zone is full, and common motive means for driving said fuel feeding means and said fuel distributing means.

8. In a cross draft stoker, in combination with a source of fuel, exterior and interior walls provided with ingress openings for combustion supporting air and egress openings for products of combustion, said openings defining a combustion supporting zone and said walls extending above said combustion supporting zone to define a fuel receiving zone from which fuel descends by gravity to replenish the fuel in said combustion supporting zone, means for elevating fuel from said source to the top of said fuel receiving zone, means movable horizontally through a closed path for distributing evenly the fuel delivered to said fuel receiving zone by said elevating means, said elevating means being constructed to deliver fuel to said fuel receiving zone at a rate in excess

of that at which the fuel is normally consumed in the combustion supporting zone, means communicating with said fuel receiving zone adjacent the path of said fuel distributing means and extending downwardly to said source of fuel for returning excess fuel to said source by gravity, said fuel distributing means operating when said fuel receiving zone is full to move excess fuel in

5 said zone to said fuel returning means, and a common motive means for driving both of said fuel elevating means and said fuel distributing means.

9. In a cross draft stoker, in combination with fuel supply means, exterior and interior walls provided with ingress openings for combustion supporting air and egress openings for products of combustion, said openings defining a combustion supporting zone and said walls extending above said combustion supporting zone to define

10 a fuel receiving zone from which fuel descends by gravity to replenish the fuel in said combustion supporting zone, means for feeding fuel to the top of said fuel receiving zone, said fuel feeding means being constructed to supply fuel to said

15 fuel receiving zone at a rate in excess of the rate at which the fuel is normally consumed in the combustion supporting zone, means movable substantially horizontally through a closed path and acting on the fuel delivered by said fuel feeding

20 means for distributing the received fuel evenly on top of the fuel in said fuel receiving zone, a fuel discharge opening communicating with said fuel receiving zone at the normal fuel level therein, said fuel distributing means moving into adjacency

25 to said opening to displace therethrough the excess fuel when said fuel receiving zone is full, common motive means for driving said fuel feeding means and said fuel distributing means, and means for discontinuing the operation of

30 said fuel supply means when a predetermined excess of fuel has been supplied thereby.

10. In a cross draft stoker, in combination with fuel supply means, exterior and interior walls provided with ingress openings for combustion supporting air and egress openings for products of combustion, said openings defining a combustion supporting zone and said walls extending above said combustion supporting zone to define a fuel receiving zone from which fuel descends by

35 gravity to replenish the fuel in said combustion supporting zone, means for elevating fuel from said supply means to the top of said fuel receiving zone, means movable horizontally through a closed path for distributing evenly the fuel delivered to said fuel receiving zone by said elevating

40 means, said elevating means being constructed to deliver fuel to said fuel receiving zone at a rate in excess of that at which the fuel is normally consumed in the combustion supporting zone, means communicating with said fuel receiving zone adjacent the path of said fuel distributing means and extending downwardly to said supply means for returning excess fuel to said supply means by gravity, said fuel distributing means operating when said fuel receiving zone is full to move excess fuel in

45 said zone to said fuel returning means, a common motive means for driving both of said fuel elevating means and said fuel distributing means, and means for discontinuing the operation of said fuel supply means when a predetermined excess of fuel has been supplied thereby.

11. In a cross draft stoker, in combination with inner and outer walls provided with tuyères to form a combustion chamber, said walls extending

upwardly above said tuyères to provide a fuel receiving chamber above the zone of burning fuel in said combustion chamber, fuel feeding means for delivering fuel to the top of the fuel in said receiving chamber, means for spreading the fuel delivered by said fuel feeding means with substantial uniformity over the top of the fuel in said receiving chamber, said fuel feeding means being constructed to feed fuel to the top of said receiving chamber at a rate greater than that at which the fuel is normally consumed in said combustion zone, said receiving chamber having a fuel discharge opening at the normal level of the fuel therein and said fuel spreading means moving into adjacency to said opening to displace therethrough excess fuel from the top of said chamber when the same is full, and motive means for driving both of said fuel feeding means and said fuel spreading means.

12. In a cross draft stoker, in combination with a source of fuel, spaced exterior and interior walls defining a combustion chamber, said exterior and interior walls having openings for the ingress of combustion air and egress of products of combustion, said ingress and egress openings defining a fuel burning zone in said combustion chamber and said inner and outer walls extending above said openings to define a fuel receiving zone above said fuel burning zone, fuel feeding means for elevating fuel to the top of the fuel in said fuel receiving zone, fuel spreading means acting on the fuel delivered to the top of the fuel in said fuel receiving zone for evenly distributing the delivered fuel on the top of the fuel in said receiving zone, said fuel feeding means being constructed to elevate fuel to the top of said receiving zone at a rate in excess of that at which the fuel is normally consumed in said combustion supporting zone, means communicating with said receiving zone and extending downwardly to said source for returning fuel to said source by gravity, said fuel distributing means moving into adjacency to the inlet to said fuel returning means and operating when said receiving zone is full to remove excess fuel from the top of said zone to said fuel returning means, and motive means for driving both said fuel feeding means and said fuel spreading means.

13. In a cross draft stoker, in combination with interior walls defining a central chamber, means for conducting products of combustion from said central chamber, exterior walls spaced from said interior walls, said exterior and interior walls being respectively provided with ingress openings for combustion supporting air and egress openings for products of combustion, said walls defining a combustion chamber with said openings defining a combustion supporting zone therein and said walls extending above said combustion supporting zone to define a fuel receiving chamber from which fuel descends by gravity to replenish the consumed fuel in said combustion supporting zone, fuel feeding means for supplying fuel to the top of said fuel receiving zone, fuel spreading means movable horizontally through a closed path for leveling the fuel in said fuel receiving chamber, and means for driving said fuel spreading means from said fuel feeding means.

14. In a cross draft stoker, in combination with a source of fuel, interior walls defining a central chamber, means for conducting products of combustion from said central chamber, exterior walls spaced from said interior walls, said exterior and interior walls being respectively

provided with ingress openings for combustion supporting air and egress openings for products of combustion, said walls defining a combustion chamber with said openings defining a combustion supporting zone therein and said walls extending above said combustion supporting zone to define a fuel receiving chamber from which fuel descends by gravity to replenish the consumed fuel in said combustion supporting zone, means for elevating fuel from said source to the top of said fuel receiving zone, fuel distributing means movable horizontally through a closed path for spreading at the top of the fuel in said fuel receiving chamber the fuel delivered by said fuel elevating means, means communicating with said receiving zone adjacent the path of said fuel distributing means and extending to said source for returning fuel to said source, said fuel distributing means operating to remove excess fuel from the top of said fuel receiving chamber to said fuel returning means, and means for driving said fuel distributing means from said fuel feeding means.

15. In a cross draft stoker, in combination with interior walls defining a central member, means for conducting products of combustion from said central chamber, exterior walls spaced from said interior walls, said exterior and interior walls being respectively provided with ingress openings for combustion supporting air and egress openings for products of combustion, said walls defining a combustion chamber with said openings defining a combustion supporting zone therein and said walls extending above said combustion supporting zone to define a fuel receiving chamber from which fuel descends by gravity to replenish the consumed fuel in said combustion supporting zone, means for feeding fuel from said source to the top of said fuel receiving zone, fuel distributing means movable horizontally through a closed path for spreading at the top of the fuel in said fuel receiving chamber the fuel delivered by said fuel feeding means, said fuel feeding means being constructed to feed fuel at a rate in excess of that at which fuel is normally consumed in said combustion supporting zone, means communicating with said receiving zone adjacent the path of said fuel distributing means and extending to said source for returning fuel to said source, said fuel distributing means operating to move excess fuel from the top of said fuel receiving chamber to said fuel returning means, and means for driving said fuel distributing means from said fuel feeding means.

16. In a cross draft stoker, in combination with a source of fuel, interior walls defining a central chamber, means for conducting products of combustion from said central chamber, exterior walls spaced from said interior walls, said exterior and interior walls being respectively provided with ingress openings for combustion supporting air and egress openings for products of combustion, said walls defining a combustion chamber with said openings defining a combustion supporting zone therein and said walls extending above said combustion supporting zone to define a fuel receiving chamber from which fuel descends by gravity to replenish the consumed fuel in said combustion supporting zone, means for elevating fuel from said source to the top of said fuel receiving chamber, said elevating means being constructed to deliver fuel to said fuel receiving chamber at a rate in excess of that at which said fuel is nor-

mally consumed in said combustion supporting zone, means movable horizontally through a closed path and disposed at the top of said fuel receiving chamber for acting on the fuel delivered by said fuel elevating means and distributing the same evenly over the top of the fuel in said fuel receiving chamber, means communicating with said chamber adjacent the path of said fuel distributing means through which excess fuel is removed from said chamber by said distributing means, and means for driving said distributing means from said fuel elevating means.

17. In a cross draft stoker, in combination with a source of fuel, interior walls defining a central chamber, means for conducting products of combustion from said central chamber, exterior walls spaced from said interior walls, said exterior and interior walls being respectively provided with ingress openings for combustion supporting air and egress openings for products of combustion, said walls defining a combustion chamber with said openings defining a combustion supporting zone therein and said walls

extending above said combustion supporting zone to define a fuel receiving chamber from which fuel descends by gravity to replenish the consumed fuel in said combustion supporting zone, means for elevating fuel from said source to the top of said fuel receiving zone, said elevating means being constructed to deliver fuel to said fuel receiving chamber at a rate in excess of that at which said fuel is normally consumed in said combustion supporting zone, means movable horizontally through a closed path and disposed at the top of said fuel receiving zone for acting on the fuel delivered by said fuel elevating means and distributing the same evenly over the top of the fuel in said fuel receiving zone, means communicating with said receiving zone adjacent the path of said fuel distributing means and extending to said source for returning fuel to said source by gravity, said fuel distributing means operating to move excess fuel from said receiving chamber to said fuel returning means, and means for driving said distributing means from said fuel elevating means.

WESTON M. FULTON.
